UNITED STATES PATENT OFFICE

RODNEY H. YALE, OF SAN DIEGO, CALIFORNIA

DAM

Application filed August 3, 1931. Serial No. 554,826.

My invention relates generally to dams for impounding water, and it is a purpose of my invention to provide a dam structurally characterized in a manner to offer the utmost safety against damage or failure by earth movement and by pressure of impounded water; to enable it to be constructed rapidly at a lower cost; and to render it capable of being thoroughly inspected whenever desired without loss of the impounded water.

It is a further purpose of my invention to provide a dam forming a monolithic concrete structure having cavities or cells occupying the larger part of its volume to provide spaces within the structure adapted to receive a substance such as the water impounded by the dam, to the end of economically adding weight to the structure functioning to aid in resisting lateral pressure of the impounded water against the structure, all while insuring the utmost strength and dependability against structural failure.

I will describe only one form of dam embodying my invention, and will then point out the novel features thereof in claims.

In the accompanying drawings:

Figure 1 is a view showing in vertical transverse section one form of dam embodying my invention.

Figures 2 and 3 are enlarged fragmentary horizontal sectional views taken on the lines 2-2 and 3-3 of Figure 1 and looking in the direction of the arrows, and

Figure 4 is an enlarged fragmentary perspective view looking at the upstream face of the dam, and

Figure 5 is an enlarged fragmentary vertical sectional view of the dam.

Referring specifically to the drawings in which similar reference characters designate similar parts in each of the several views, the dam embodying my invention is formed by casting on a suitable foundation 10 at the dam site, a body 11 of concrete forming a monolithic structure. Suitable forms (not shown) are of course employed for this purpose; and as the casting operation progresses, cavities in the form of vertically disposed tubular cells 12 arranged in rows extending longitudinally and transversely of the struc-

ture. The lower ends or bases 13 of the cells are closed by a layer of concrete of the necessary thickness which rests directly upon the foundation 10.

Sealing elements 14 in the form of deep cups of seamless steel tubing with bottoms 15 welded therein, are cast in place during the initial pouring of concrete, to line the bottoms and lower portions of the cells and thus seal the latter against leakage of water into the foundation.

The top surface of the body may be stepped as illustrated in Figure 1 so that the cells will progressively increase in height from the upstream face of the structure, the last few longitudinal rows of cells being of equal height and extending to the maximum height of the dam. The upper ends of all these cells are open and the last few above mentioned rows are preferably covered by a concrete slab 16 to form a suitable roadway.

The upper ends of the remaining longitudinal rows of cells, which respectively open to the horizontal surfaces of the steps 17, may be covered with concrete closure plates 18 secured in place on the steps and having openings 19 therein to enable water from that impounded by the dam, to flow into the cells and balance the water pressures above the covers and within the cells.

Other and relatively small vertically disposed and tubular cells 20 and 21 extend alongside the cells 12 to provide with the latter, sufficient water spaces within the body of concrete to form the major portion of the volume of the latter in order to minimize the quantity of concrete necessary for the dam. The upper ends of the cells 20 and 21 are also open and are adapted to receive water through the openings 19 of the closure plates 18. The lower ends of these cells are constructed in the same manner as the cells 12 so as to be sealed against leakage of water into the foundation.

During the casting operation, suitable pipes are imbedded in the walls of the several groups of cells 12, 20 and 21 to provide ducts 22 at successive levels or intervals along the lengths of the cells so as to place the cells in communication with each other and with

the space to be occupied by water behind the dam, thus permitting the cells to automatically fill with water to the same level as that of the impounded water.

- 5 Tie members 23 in the form of annular metal bands connected by bars 24 are imbedded in the concrete body at intervals throughout its height so that the members are disposed in surrounding relation to the 10 cells 12 and co-act with the bars 24 in binding the body together into a monolithic unit. Intermediate the tie members, separate metal rings 25 may be imbedded in the walls of the cells 12 to further reinforce the structure.
- 15 Other reinforcements such as metallic rods (not shown) may also be imbedded in the body as desired.

It will be appreciated that the body may be constructed of uniform height throughout its 20 width rather than stepped as illustrated and that the upper open ends of the cells may or may not be covered as desired. The dam may be built with a straight or arched face and a suitable spillway provided as required.

25 When the reservoir is filled to the highest level it is intended the impounded reservoir water shall reach all cells in the dam and foundation will be filled automatically with water, from the base of the foundation upwardly, and the impounded water will stand over the tops of the shorter tubes that do not extend the full height of the dam.

The weight of the water on the bases of the cells will be the same with the shorter cells 35 as with the cells extending the full height of the dam, as the water standing over the tops of the shorter tubes will represent the same weight and exert the same pressure in those tubes and on their bases as it would if such tubes extended the full height of the highest tubes. That is to say, the weight on the bases of all the cells, short or long, will be the same; and this result will be the same, with the tops of said shorter cells, open or covered, provided the covers, if used, are provided with the openings 19 over each cell, to permit the communication of the water above the cells with the water in the cells, and thus equalize the pressure on such covers under and upper 50 sides.

There are no such strains and stresses on the concrete structure of this dam, as with other dams using a minimum of concrete, as the walls of the vertical tubular cells of this 55 dam are subject to comparatively no lateral strains or stresses, except on the outer halves of the outer row of such cells, at the rear or down stream side of the dam; and on these outer halves there is only such quiet hydrostatic pressure against these outer walls, as would be found in any cell of equal diameter, containing quiet water of equal height. The 60 walls of all cells in the interior of the dam are relieved of lateral pressure or stress, as 65 each of such cells containing water, is sur-

rounded by other cells containing water of equal height, thus neutralizing such pressure. The front row of cells, next to the impounded reservoir water, is backed and adjoined by other cells containing water of equal height 70 and pressure, except at their front sides, and here the impounded reservoir water exerts a pressure not exceeding the pressure on the interiors of this front or upstream row of cells as the water is the same height in both 75 instances. The outer row of cells at each end of the dam is backed at its outer side by the banks of the stream or canyon sides.

It will be seen and understood from the foregoing that while the water in the vertical cells extends continuously from the bases of the cells resting on the bed-rock or other earth structure supporting the foundation, to the top level of the impounded reservoir water, without any intervention of other 85 substance or material; the concrete also continues uninterruptedly from said earth structure which the foundation rests upon, upwardly to the topmost parts of the dam. That is to say, water rests upon water and concrete rests upon concrete.

It is practicable, and sound practice, to confine water in cells or cavities within a concrete dam structure to provide weight to resist the lateral or horizontal pressure of the 95 impounded reservoir water. In fact it is more practicable than to build a dam entirely of concrete to resist such pressure by weight, as to use such large amounts of concrete as would thus be required the cost would 100 be high and the curing of concrete in large masses involves problems somewhat unknown in such interiors. With my dam, proper and prompt curing of the concrete is assured, as the air can reach all surfaces interior and exterior and there are no bulky sections. There are no compression problems or conditions in connection with the use of water for the purposes named in the foregoing paragraphs, as water is practically incompressible.

Of course substances other than water could be used to fill the tubes of this dam to provide weight, such as gravel, sand or broken rock, or the like, but these latter materials would represent considerable cost, as even though available at the dam site, they must have some preparation and must be moved to the tubes, all of which represents cost of labor, if not of materials; while the water costs comparatively nothing and moves by gravity to the cells. Furthermore, if either of the materials other than water are used, they will compress of their own weight and therefore be reduced in volume 115 while the water always fills the cells to the level of the impounded reservoir water automatically.

If substances other than water are used to fill the cells of the dam, the ability to empty 120

the cells for inspection of interiors is foregone; while if the filler is water this can be accomplished conveniently.

Inasmuch as each main cell 12 is individually strong enough from bottom of foundation to the top of the structure, to withstand without contiguous support any internal pressure that it can be subjected to, these cells may be pumped empty one by one or in groups for internal personal inspection if necessary or desired, even when the dam is in use, and this feature might prove of great value in event of damage or supposed damage by earthquake. This dam should be comparatively safe and immune from earthquake damage, and should such damage occur it may be repaired internally or externally.

The conditions relating to the walls of the vertical cells, and the water pressure, are the same in the foundation portion of the dam as in the portion above the stream bed level; except that the sides of the excavation for the foundation support the outer walls of the outer rows of the tubular cells at the front, rear, and ends of said foundation.

The use of water in the foundation portion of the vertical tubular cells is as practicable and desirable as in the other portions of the dam, and there is no reason why there should be any other material interposed between the water in the upper portions of the cells and the base of the foundation resting on the earth structure selected to carry the dam and foundation. Water is the best and most practicable medium to carry the weight of the water from its highest level in the dam right on down to the bases of the tubular cells resting upon the earth structure selected to carry the foundation of the dam.

The weight of the water in the cells on the foundation is automatically lessened as the level of the impounded reservoir water lowers. When weight is the principal resistant to the lateral pressure of the impounded reservoir water, there is obviously no such strains or stresses imposed on the materials used as with dams wherein such pressure is borne principally by the inherent strength of the materials in the buttresses, walls, aprons and like parts, used to transmit such pressure to its ultimate lodgment on the base of the foundation or on the canyon walls.

The ultimate place and source of resistance in this dam as with other dams is, after all, the earth structure at the base of the foundation, or the earth structure at the canyon sides, and in my dam the principal resistant to the pressure of the impounded reservoir water is the weight of water and concrete composing the dam and resting upon the earth structure at the base of the foundation which, in the present form, represents in actual weight about 400 pounds for each 100

pounds of concrete used in the dam and foundation.

The weight supplied by water for each 100 pounds of concrete used could be increased by increasing the diameters of the cells or lessening the thickness of the walls of the cells, or both, but such procedure would reduce the structural strength of the dam. The strength of the walls of the cells and the general structural strength should be maintained sufficiently so that each individual cell or a group of cells could be pumped empty for inspection or repair, while the dam is in use, without materially detracting from its stability or safety. For instance, should one or more of the cells in the outer row at the rear or down stream side of the dam be damaged by earthquake or otherwise, they may be pumped empty for repair, while the dam is under full pressure from the impounded reservoir as the load carried by them will be at once and automatically taken over by the next row of cells.

There are well known and defined laws governing water, and it is well known and established, as to just what is necessary in materials and construction to safely confine in a tube, a column of water of any given height. Water is safely and securely confined in tubes with a minimum of material. Other forms may obviously be substituted, but more material will be required for equal security.

Conveying water from the impounded reservoir water to all cells throughout the dam is an important feature and the supplying of water automatically in this manner is an inexpensive method of providing weight, and as the horizontal ducts used for this purpose are of relatively small diameter, their use does not detract from the structural strength of the walls of the cells or other concrete parts of the dam. The supplying of water in such manner does not in any way or degree detract from the individuality of the cells as a source of weight for resistant purposes entirely separate in an effective resistant sense from the impounded reservoir water. Also the function served by these small horizontal tubes, of the automatic rising or lowering of the water in the cells, in conjunction with the rising or lowering of the level of the impounded reservoir water, is important.

All solids are compressible, in some degree while water is practically incompressible and a most suitable substance to use within a dam for weight resistant purposes.

As only a minimum of concrete and a minimum of form work is required and consequently a minimum of labor, the cost is low, and rapid completion should be possible.

Provision for the inspection of interiors, while the dam is under full pressure, is a valuable advantageous feature of this dam.

The usual precautions generally followed with other dams to keep water from seeping

under the base of the foundation will be taken with this dam.

Compression or tension problems cause no concern with this dam and there are no unusual or unknown forces, elements or problems to be considered or met.

Inasmuch as this dam is more stable and safer, due to the use of weight as the principal resistant, and the use of broader foundation with the employment of less materials and labor it is a superior dam.

Although I have herein shown and described only one form of dam embodying my invention, it is to be understood that various changes and modifications may be made therein without departing from the spirit of the invention and the spirit scope of the appended claims.

I claim:

20. 1. A dam comprising a monolithic body having substantially vertically disposed tubular cells representing the major portion of the volume of the body, and impervious metallic sealing tubes having closed bottoms and lining the bottoms and lower portions of the side walls of the cells.

2. A dam comprising a monolithic body having substantially vertically disposed tubular cells representing the major portion of the volume of the body, and tie members imbedded in the body in surrounding relation to the cells and connected together.

3. A dam comprising a monolithic structure having vertically disposed tubular cells progressively increasing in height from the upstream face of the structure and adapted to contain a substance adding weight to the structure to aid in resisting lateral pressure of impounded water against the structure.

40. 4. A dam comprising a monolithic structure having vertically disposed tubular cells progressively increasing in height from the upstream face of the structure and exposed to water impounded by the dam so as to add weight to the structure to aid in resisting lateral pressure of impounded water against the structure.

50. 5. A dam comprising a monolithic structure having vertically disposed tubular cells progressively increasing in height from the upstream face of the structure, the upper ends of the cells being open and the cells being intercommunicating so as to receive water from that impounded by the dam.

55. 6. A dam having its top surface stepped in a direction upwardly from the upstream face of the dam, the dam having vertically disposed tubular cells opening at their upper ends to the steps and having their lower ends closed.

7. A dam having its top surface stepped in a direction upwardly from the upstream face of the dam, the dam having vertically disposed tubular cells opening at their upper ends to the steps and having their lower ends

closed, and means by which the cells are rendered inter-communicating.

8. A dam having its top surface stepped in a direction upwardly from the upstream face of the dam, the dam having vertically disposed tubular cells opening at their upper ends to the steps and having their lower ends closed, the walls of the cells having ducts at intervals along the lengths of the cells to place the cells in communication with each other.

9. A dam having vertically disposed tubular cells progressively increasing in height from the upstream face of the dam and open at their upper ends to the space to be occupied by impounded water.

10. A dam having vertically disposed tubular cells progressively increasing in height from the upstream face of the dam and open at their upper ends to the space to be occupied by impounded water, and ducts in the vertical walls of the cells for placing the latter in communication with each other.

11. A dam comprising a monolithic body having substantially vertically disposed tubular cells representing the major portion of the volume of the body, the cells extending continuously from the top of the dam to its base on the earth structure supporting the dam, said cells progressively increasing in height from the upstream face of the dam and being exposed to water impounded by the dam so as to add weight to the body to aid in resisting the lateral pressure of impounded water against the dam.

12. A dam having substantially vertically disposed tubular cells progressively increasing in height from the upstream face of the dam and in communication with the space to be occupied by impounded water and extending continuously from the base of the dam on the earth structure supporting the foundation to the top of the dam.

RODNEY H. YALE.
